UNITED STATES PATENT OFFICE.

SWITS CONDÉ, OF OSWEGO, NEW YORK.

DESIGN FOR KNIT DRAWERS.

SPECIFICATION forming part of Design No. 11,636, dated February 3, 1880.

Application filed December 4, 1879. Term of patent 7 years.

To all whom it may concern:

Be it known that I, SWITS CONDÉ, of Oswego, in the county of Oswego, in the State of New York, have invented new and useful Improvements in a Design for Knitted Drawers, of which the following, taken in connection with the accompanying drawing, is a full, clear, and exact description.

The design consists in a peculiar combination and arrangement of a series of horizontal bars of equal lengths, separated from each other by square blocks interposed between the adjacent ends of the respective bars, and of equal height therewith. Each succeeding series of bars and blocks is arranged to bring its blocks over the center of the bars of the preceding series. The bars are of sufficient lengths to cause them to lap onto the ends of the bars of the adjacent series.

The square blocks (indicated by the letter *a* in the drawing) are of one color only, and the bars *b* are composed of three straight and parallel stripes, the central stripe of which is of the same color as the square blocks, and the two outer stripes are of one color different from the central stripe.

Having thus described my invention, what I claim, and desire to secure by Letters Patent, is—

The design for knit drawers, consisting of a series of bars and square blocks arranged alternately and horizontally on the garment, each series having its blocks over the center of the bars of the adjacent series, the blocks composed of one color and the bars of three stripes, the central stripe of which is of the same color as the block, and the two outer stripes of one color different from that of the central stripe, substantially as described, and shown in the accompanying illustration.

In testimony whereof I have hereunto signed my name and affixed my seal in the presence of two attesting witnesses, at Oswego, in the county of Oswego and State of New York, this 18th day of November, 1879.
